UNITED STATES PATENT OFFICE.

MAX ALTSCHULER, OF NEW YORK, N. Y., AND SAMUEL M. VINES, OF WESTFIELD, NEW JERSEY, ASSIGNEES TO ALTSCHULER BROS., OF NEW YORK, N. Y., A FIRM COMPOSED OF SOLOMON ALTSCHULER AND MAX ALTSCHULER.

UMBRELLA.

1,195,635.

Specification of Letters Patent. Patented Aug. 22, 1916.

Application filed December 30, 1914. Serial No. 879,635.

To all whom it may concern:

Be it known that we, MAX ALTSCHULER, a citizen of the United States, and a resident of the borough of Brooklyn, county of 5 Kings, city and State of New York, and SAMUEL M. VINES, a citizen of the United States, and resident of Westfield, county of Union, State of New Jersey, have jointly invented a certain new and useful Improvement 10 in Umbrellas, of which the following is a specification.

Our invention relates to umbrellas and has for its object to provide a construction which is extremely rigid in the raised condition of the umbrella, and which reduces 15 the tendency of the latter to turn inside out under a violent wind pressure to a minimum.

Our improvement further contemplates constructing the umbrella in such a manner 20 that it may be readily returned to normal condition if it should turn inside out under excessive strains and also in a manner to permit the umbrella to be readily and compactly closed when not in use.

25 Our improvement will be fully described hereinafter and the features of novelty will be pointed out in the appended claims.

Reference is to be had to the accompanying drawings in which—

30 Figure 1 is a skeleton view of our improvement showing the umbrella raised; Fig. 2 is a similar view of the umbrella in its closed condition; Fig. 3 is a detail view similar to Fig. 1 on an enlarged scale; Fig. 35 4 is an enlarged detail view of the braces; Fig. 5 is a longitudinal section thereof and Fig. 6 is a diagrammatic sectional view showing the parts in the positions occupied if the umbrella should turn inside out.

40 In the drawings 10 represents the usual umbrella rod or stick provided at its one end with any suitable type of handle 11 and carrying an upper crown 12 near its opposite end, the latter being radially slotted to accommodate the ends of the ribs 13 secured in connection with said crown 12 in any well known way. The present construction includes main braces 14 which at one end are 45 pivotally connected at 15 with the ribs 13

50 and at their opposite ends are pivotally secured at 16 to an intermediate crown 17 forming part of or secured to a main runner 18 adapted to slide lengthwise of the rod 10 as clearly shown in Fig. 3. These main

braces 14 are made in the form of channel 55 or trough like members and in consequence are extremely rigid and firm against strains tending to bow or buckle the same. As clearly illustrated in Figs 1 and 3, the runner 18 instead of terminating substantially at the intermediate crown 17 extends a considerable distance beyond the same to form a continuing sleeve 19, the purpose of which will be more clearly brought out hereinafter and which together with the 60 runner 18 constitutes what might be termed a floating ferrule, the usual stop for limiting the upward movement of the runner in ordinary umbrellas being omitted. Auxiliary braces 20 have their one end pivotally 65 connected at 21 with the main braces 14 and their opposite ends pivotally secured at 22 to a lower crown 23 forming part of or secured to an auxiliary runner 24 adapted to freely slide lengthwise of the runner 18. 70 These auxiliary braces 20 are preferably made of flat material, the ends of which are twisted at right angles to the main portion 75 thereof to provide the proper pivotal connections with the said main braces 14. With 80 this construction in the folded condition of the umbrella, the one twisted end of each auxiliary brace extends into a channeled main brace 14 while the main portion of each auxiliary brace 20 lies flat against the said 85 main braces thus permitting a ready and compact closing of said umbrella without interference. The customary catches 25 and 26 are provided at proper points on the rod 10 for maintaining the main runner 18 in 90 its raised or lowered position when the umbrella is open or closed, while the usual material 27 is secured to the ribs by stitches 28 or other fastening means located at intervals along said ribs as indicated in Fig. 1. 95

It will readily be seen that, if a wind pressure tending to reverse or turn the raised umbrella inside out occurs beneath the same, the said pressure will cause the main runner 18 to ride up on the rod 10 until the upper 100 end of the sleeve 19 contacts with the upper crown 12. During this movement the braces 14 draw the ribs 13 approximately to the positions shown by dotted lines in Fig. 3, with the free end portions thereof moved 105 nearer to the rod, thus counteracting the tendency of said free ends of the ribs to turn or reverse themselves under such wind pres-

sure and consequently checking the tendency of the umbrella to reverse itself. At the same time the auxiliary runner 24 will be free to move lengthwise of the main runner 18 in order to accommodate itself as well as the auxiliary braces 20 to this abnormal movement of the floating ferrule.

If the pressure should be sufficient to turn the umbrella inside out the reversing of the 10 ribs 13 will take place substantially only at their free end portions or from the pivots 15 outwardly, the remainder of said ribs retaining approximately the original curvature which they have in the normal, raised condition of the umbrella. With this arrangement the umbrella may be turned back to its proper raised position by simply resting the free ends of the reversed ribs 13 on a flat surface and then pressing downwardly on 20 the rod 10, whereupon said ribs will easily snap back to their intended normal condition this operation being assisted by the covering material 27 and the attaching means 28. The construction and arrangement shown and described also presents a rigid maximum resistance to pressure exerted from above or outside of the umbrella as will be readily apparent.

Our improved umbrella is capable of being operated in the same manner as an umbrella of ordinary construction and at the same time may be folded compactly and rolled to as small a diameter as any ordinary umbrella.

Various changes in the specific construction shown and described may be made within the scope of the claims without departing from the spirit of our invention.

We claim:

40 1. In an umbrella, the combination of a rod, an upper crown upon said rod, continuous ribs attached to said upper crown,

Copies of this patent may be obtained for five cents each, by addressing the "Commissioner of Patents, Washington, D. C."

a main runner slidably mounted on said rod, an intermediate crown carried by said main runner, a sleeve forming a continuation of 45 said main runner above said intermediate crown and with said main runner constituting a floating ferrule adapted to abut against said upper crown to limit an abnormal upward movement of said main runner, continuous main braces connected with said ribs and with said intermediate crown, an auxiliary runner slidably mounted on said main runner, auxiliary braces connected with said main braces near their inner ends and with 55 said auxiliary runner at its upper end, and a covering material attached to said ribs at intervals throughout the length thereof.

2. In an umbrella the combination of a rod, a ferrule slidably thereon, ribs pivotally attached to said rod, main braces pivotally attached to said ribs and to said ferrule and approximately trough shaped in cross-section, an auxiliary crown slidably mounted on said ferrule, and flat auxiliary braces 60 having one end pivotally connected with said auxiliary crown and their opposite ends twisted about the axis of said auxiliary braces to extend at approximately right angles to the major portions thereof, said 65 twisted ends being pivoted to said main braces and extending into the troughs thereof and said major portions of said auxiliary braces being adapted to lie flat against the open mouths of said troughs in the folded 70 condition of the umbrella.

In testimony whereof we have hereunto set our hands in the presence of two subscribing witnesses.

MAX ALTSCHULER.
SAMUEL M. VINES.
